[57] CLAIM

The ornamental design for a compact disk holder, as shown and described.

DESCRIPTION

FIG. 1 is a perspective view of the invention as opened, showing my new design;

FIG. 2 is a front elevational view thereof shown in a closed position;

FIG. 3 is a right side elevational view of FIG. 2;

FIG. 4 is a rear elevational view of FIG. 2;

FIG. 5 is a top plan view of FIG. 2, and,

FIG. 6 is a bottom plan view of FIG. 2.
